UNITED STATES PATENT OFFICE.

WILLIAM W. COZZENS, OF SAN JOSE, CALIFORNIA.

EVAPORATOR.

Application filed December 4, 1922. Serial No. 604,879.

To all whom it may concern:

Be it known that I, WILLIAM W. COZZENS, a citizen of the United States, and a resident of San Jose, county of Santa Clara, 5 and State of California, have invented a new and useful Evaporator, of which the following is a specification.

The present invention relates to improvements in evaporators and has particular reference to evaporators or driers such as are commonly used for the drying of fruit. I do not wish, however, to be confined to this one function, it being apparent that the same device may be used in other connections. The particular object of the invention is to provide an evaporator of the character described in which the air current can be readily regulated so as to pass over the fruit to be dried in different directions and 20 to thereby insure an even drying of the fruit. A further object of the invention is to provide means whereby the air current can be deflected from its natural course and guided over those portions of the fruit containers 25 which normally would not be subjected to sufficient draft to dry as quickly as fruit disposed in other portions. A further object of the invention is to provide means for reheating the air currents at an intermediate 30 station so as to enable the same to absorb further moisture during the continuation of their travel. It is further proposed to provide special means allowing the fruit to be 35 inspected during the drying process without seriously interfering with the drying operation. Other objects and advantages of the device will appear as the specification proceeds.

With these objects in view I have shown 40 the preferred form of my invention in the accompanying drawing in which Figure 1 represents a plan view of the drier showing the position of the various parts constituting the same, Figure 2 a cross section through 45 the drier along line II-II of Figure 1, Figure 3 a side elevation of a portion of the drier and Figure 4 a detail view in longitudinal section of a car used with the same. While I have shown only the preferred form 50 of the invention I wish to have it understood that various changes or modifications may be made within the scope of the claims here- 55 to attached without departing from the spirit of the invention.

My drier (1) is illustrated in Figure 1 as comprising a large building (2) preferably

of wood and as containing four different units (3, 4, 6 and 7) each two units arranged in parallel relation forming one set. The two sets are arranged in longitudinal alignment. It should be understood that each unit may be used by itself, the arrangement shown in Figure 1 being particularly adapted for larger plants. Tracks (8 and 9) extend throughout the building along side of the drying sections and cars (11), one of which is shown in Figure 4 are adapted to be moved back and forth on those tracks. These cars are of standard make and in common use and need no further description. 60 They are provided with transverse tracks (12) on which are supported cars (13) and which can be made to register with any of the transverse tracks (14) leading into the drying sections. The trays (16) on which the fruit to be dried is spread are stacked on the latter cars and held in spaced relation to each other by means of suitable spacing members (17). The interior portion of the drier is adapted to be separated 65 from the remainder by means of drop doors (18) sliding in posts (19) and counterbalanced by any suitable means to facilitate their handling as by the counter-weights (21). When the doors are closed a central 70 tunnel is provided thereby which extends 75 from one end of the building to the other and in which the drying operation takes place.

To dry the fruit quickly I provide a furnace (23) at either end. The heated air rising from the furnace is passed through the flue (24) into the blower (26) which latter is driven by a motor (27) or any other suitable means. The blower discharges directly into the drying tunnels, the shields (28) and the end baffles (29) guiding the air directly to the cars on which the fruit is stacked. A swinging deflector (31) is provided for determining the direction of the air currents. As this gate is disposed in its central position the air will pass through both sides of the tunnel in equal quantities, but when the deflector is swung into one of its extreme positions it shuts off one of the sides and forces the air to pass through the other side. Considering the first two parallel units by themselves and the communication between these and the next units as being closed the air currents will be turned at the end of the tunnel and returned along the other side to be discharged through a

door (32). If the deflector (31) is set to occupy its central position so that the air currents pass through both sides of the tunnel simultaneously a suitable outlet (33) is provided at the other end.

Doors (34) are provided between the two sets of drying units and when these doors are opened the air currents are preferably caused to travel from one end of the tunnel to the other along one side, each of the two blowers supplying one side with heated air currents. If the drier is of considerable length I preferably provide a steam or hot water heater (36) in the central portion of the drier which serves to reheat the air currents and to allow the same to absorb further moisture.

It has been found by experience that fruit stacked in the manner herein described and subjected to air currents in a tunnel is apt to dry more quickly near the ends of the trays than in the central portion of the same due to the fact that the air currents pass more freely over the end portions. Suitable means should therefore be provided to avoid this feature and to cause an even drying of the fruit which is essential for the attainment of good results. For this purpose I provide baffles (38) between the cars which extend from the posts (19) and from posts (39) disposed along the center line of the drier into the spaces between the cars so as to force the air currents to pass between the trays rather than around the same. These baffles are preferably provided with shutters (41) which are adjustable by means not shown and which allow the flow of the air currents to be regulated.

For the inspection of the fruit during the drying operation I provide small sliding doors (42) within the main doors. If the former are opened the operator is in a position to view the fruit or to take some of it from the trays for the purpose of inspection.

It is desirable sometimes to turn the fruit end for end to insure an even evaporation and for this purpose I provide suitable turn tables (44) which allow the whole car to be turned end for end.

Claims—

1. An evaporator of the character described comprising a tunnel having a plurality of tracks transversely arranged therein and in spaced relation along the tunnel, a plurality of cars on the tracks having tiers of fruit trays thereon adapted to be introduced into the tunnel through doors along the side thereof, means for blowing heated air through the tunnel and means positioned adjacent the ends of the cars when in the tunnel for controllably deflecting the heated air toward the cars.

2. An evaporator of the character described comprising a tunnel having a plurality of transversely extending tracks therein spaced along the tunnel, a plurality of cars on the tracks adapted to be introduced into the tunnel from doors along the side thereof, means for blowing air through the tunnel, air deflecting wings pivotally supported along the sides of the tunnel positioned at the ends of the cars when in the tunnel, said wings having adjustable shutters thereon for varying the deflection of the air.

3. An evaporator of the character described comprising two sets of tunnels, the tunnels of each set being substantially parallel one to the other and the sets being longitudinally aligned in abutting relation, and the tunnels in each set being open to each other at both ends, a plurality of transversely arranged tracks in each tunnel spaced substantially along the length of the tunnels, doors along the sides of the tunnels for admitting fruit carrying cars to any of said tracks, a source of heated air at the remote ends of each set of tunnels and means for forcing the heated air toward adjacent ends of the sets, and vents disposed near the center of the sets for permitting the air to escape.

4. An evaporator of the character described comprising two sets of tunnels, the tunnels of each set being substantially parallel one to the other and the sets being longitudinally aligned in abutting relation, and the tunnels in each set being open to each other at both ends, a plurality of transversely arranged tracks in each tunnel spaced substantially along the length of the tunnels, doors along the sides of the tunnels for admitting fruit carrying cars to any of said tracks, doors at the abutting ends of the tunnels, a source of heated air at the remote ends of each set cooperating means for selectively blowing the heated air from opposite remote ends of the tunnels toward their abutting ends or of guiding the air straight through two of the abutting tunnels in one direction and through the other two in the opposite direction.

5. In a structure as defined in claim 4, means at the abutting ends of the tunnels for reheating the air passing therethrough.

6. In an evaporator of the character described, a tunnel having a plurality of tracks arranged transversely therein and spaced substantially along the length of the tunnel, doors along the side of the tunnel to admit cars to any of the tracks and smaller doors within said doors for testing purposes.

WILLIAM W. COZZENS.
